INDICATOR LAMP

Jesse R. Hollins, Brooklyn, N. Y.

Application August 30, 1949, Serial No. 4,765

Term of patent 14 years

(Cl. D48—32)

To all whom it may concern:

Be it known that I, Jesse R. Hollins, a citizen of the United States and a resident of the Borough of Brooklyn, in the county of Kings and State of New York, have invented a new, original, and ornamental Design for Indicator Lamps, of which the following a specification, reference being had to the accompanying drawing forming part hereof, in which:

Fig. 1 is a front view of an indicator lamp, showing my new design;

Fig. 2 is a side view of the same;

Fig. 3 is a rear view of the same; and

Fig. 4 is a cross sectional view taken on the line 4—4 of Fig. 1.

The dotted lines shown in the drawing are for illustrative purposes only.

I claim:

The ornamental design for an indicator lamp, as shown and described.

JESSE R. HOLLINS.
